UNITED STATES PATENT OFFICE

WILLIAM JOHN COOK, OF BERWYN, ILLINOIS, ASSIGNOR TO WESTERN ELECTRIC COMPANY, INCORPORATED, OF NEW YORK, N. Y., A CORPORATION OF NEW YORK

APPARATUS FOR FORMING OUTLETS

Application filed May 10, 1928, Serial No. 276,538. Renewed January 3, 1930.

This invention relates to apparatus for forming outlets, and more particularly to an apparatus for forming outlets in concrete floor slabs and the like.

5 In the construction of concrete floors for factories, office buildings and the like, it is the practice in some instances to mold a plurality of ducts or passageways in the concrete for subsequently housing the electrical distributing cables or conductors serving the various machines or apparatus located within the building. These passageways terminate in suitable outlets conveniently situated with respect to the locations 10 of the apparatus or machines to be served. It has heretofore been the practice in some instances to determine in advance the probable location of the various machines and mold the necessary outlets in the concrete 15 at the predetermined locations at the time the floor is constructed. However, it is sometimes difficult to determine previously to the laying of a concrete floor the particular position each machine will subsequently 20 occupy and it is often necessary to move machines from one location to another after the floor is completed. Hence, the positions of the floor outlets for electrical conductors to serve such apparatus cannot readily be 25 determined in advance, and thus the problem is presented of providing outlets after the floor has been laid.

The principal objects of the present invention are to provide a simple and inexpensive 30 apparatus for forming distributing outlets in concrete floor slabs and the like.

In accordance with the general features 35 of the invention as embodied in the formation of outlets in concrete floor slabs having unlined passageways molded therein containing a previously installed cable, a portion 40 of the slab above the passageway to which access is desired is removed and a removable collapsible form adapted to enclose the previously installed cable is inserted 45 therein. An anchor member encircling the collapsible form is positioned in place below the upper surface of the concrete and the remaining space around the 50 form is then filled in with fresh concrete,

thus forming an unlined outlet with the anchor member embedded therein. After the concrete has settled, the collapsible form is removed, an outlet fixture is secured to the anchor member, and the cable or conductor is threaded through the passageway and upwardly through the outlet guide. The outlet may be conveniently closed when not in use by removing the outlet fixture and securing a cover plate to the anchor 55 member. 60

An improved collapsible form embodying the features of the present invention comprises a pair of oppositely disposed hollow metallic members and a cooperating wedge-shaped hollow member positioned therebetween, the latter being provided with a depressed handle to facilitate its removal. The lower end portions of these members are designed to extend into the passageway and are grooved so as to straddle or surround any cables or conductors which may have been previously introduced in the passageway. 65 70

Other features and advantages of the invention will become apparent from the following detailed description, reference being had to the accompanying drawings, wherein

Fig. 1 is a fragmentary plan view illustrating one type of a concrete floor construction wherein the present invention may be advantageously employed; 80

Fig. 2 is an enlarged fragmentary vertical section taken on line 2-2 of Fig. 1; 85

Fig. 3 is a fragmentary vertical section taken on line 3-3 of Fig. 2;

Fig. 4 is a perspective view of the improved collapsible form with the individual sections shown separated from each other in order to more clearly illustrate their construction; 90

Fig. 5 is an enlarged fragmentary vertical section taken on the same line as Fig. 3 showing a portion of the concrete slab removed and the collapsible form together with the anchor plate located in place preparatory to the forming of an outlet; 95

Fig. 6 is a plan view of the positioned, 100

collapsible form and anchor plate, as shown in Fig. 5;

Fig. 7 is a fragmentary vertical section showing a completely formed outlet with an outlet fixture associated therewith for guiding a cable threaded therethrough from the horizontal passageway;

Fig. 8 is a fragmentary vertical section taken on line 8—8 of Fig. 7, and

Fig. 9 is a fragmentary vertical section similar to Fig. 7 showing a covering plate secured in position to seal an outlet when its use is no longer required.

Referring now to the drawings wherein reference numerals designate corresponding parts throughout the several views, it will be observed that Fig. 1 discloses a floor construction comprising an upper layer of wooden blocks 20 resting upon a concrete slab 21. Along the margins of the floor are terminal trenches 22 and extending through the concrete slab at an angle of substantially forty-five degrees with respect to the trenches are a plurality of unlined passageways 24 which are arranged in parallelism and terminate in the trenches. These passageways 24 may be formed within the concrete slab 21 in any convenient manner, such for example, as by molding by means of removable forms at the time the floor slab is laid. A plurality of machines, desks or other apparatus denoted by the reference numerals 25, 26, 27 and 28 are indicated diagrammatically by rectangles in Fig. 1 and positioned in proximity to each of these machines is an outlet fixture 30 each of which is associated with a passageway 24. Armored cables of conductors 31, 32, 33 and 34 for serving the machines 25, 26, 27 and 28, respectively, are threaded through the horizontal passageways 24 and upwardly through the associated outlet fixtures 30. These cables terminate in suitable switch boxes 35 mounted within the trenches 22.

It is to be understood that the present invention is not limited to the specific floor construction herein illustrated and described, but may be employed to advantage in providing outlets for associating various types of outlet fixtures with previously constructed ducts or passageways of various forms.

In order to associate an outlet fixture 30 with a previously formed passageway 24, it is first necessary to remove several of the wooden floor blocks 20, as shown in Fig. 5. A portion of the concrete slab 21 above the passageway is then broken away to present an opening of sufficient size to permit the insertion of a collapsible molding form. A molding form embodying the features of the present invention comprises a pair of oppositely disposed, hollow, aluminum castings 36 and 37 and an intermediate wedge-

shaped, hollow aluminum casting 38 (Fig. 4). A rib-like portion 39 extending across the upper portion of the wedge-shaped section 38 with its upper surface flush with the upper edge of the wedge section serves as a handle for facilitating the removal of the form after the outlet has been molded. The lower portions of the sections 36, 37 and 38 are cylindrical in shape to conform with the cylindrical cross-section of the passageways 24 and are grooved as indicated at 40 (Figs. 4 and 5) for a purpose which will presently be described.

It may be desired, for example, to install a machine, desk or apparatus in the position indicated in Fig. 1 by the rectangle 42 and in order to conveniently serve such apparatus it may be necessary to provide an outlet for associating an outlet fixture with the nearest passageway 24 at the position indicated by the dotted outline 41. By referring to Figs. 1, 2 and 3, it will be observed that this passageway 24 already contains a cable 34 previously introduced therein for the purpose of serving the apparatus or desk 28. Thus the problem is presented of providing an outlet for a passageway containing a previously installed cable. This is accomplished in a very simple and economical manner by employing the improved molding form which, as hereinbefore described, is provided with the groove 40 for surrounding the cable 34 as clearly shown in Fig. 5.

In introducing the collapsible molding form into a passageway 24, after several of the wooden floor blocks 20 and a portion of the concrete slab 21 have been removed, the sections 36 and 37 of the form are first lowered into position and then the central, wedge-shaped section 38 is introduced therebetween. An anchor plate 43 and a filler member 44 are clamped to the underside of a pair of positioning strips 45 by means of screws 46. These assembled parts are then lowered into position over the collapsible form until the strips 45 rest upon the upper surface of the concrete slab 21. It will be apparent that the strips together with the spacing or filler member 44 serve to position the anchor plate 43 a predetermined distance below the surface of the slab 21. After the anchor plate has been thus positioned, a clamping bolt 48 is threaded through registering apertures 49 provided in the individual sections of the form to firmly secure them in a fixed position. Concrete or cement is then poured around the anchor plate 43 and filler member 44 so as to completely fill all remaining spaces (Fig. 5). After the concrete has set the collapsible form is removed by first withdrawing the bolt 48 and then lifting the central wedge-shaped section 38 by means of the depressed handle 39. Having removed the central section 38, the sections 36 and

37 may be conveniently removed and by withdrawing the screws 46, the positioning strips 45 and the filler member 44 may also be removed. An outlet fixture 30 may now 5 be secured to the anchor plate 43 which is provided with a plurality of angularly projecting flanges 52 by means of which it is rigidly embedded in the concrete.

The outlet fixture 30 (Figs. 7 and 8) 10 comprises a tubular member 52 having an outwardly projecting flange 53 formed at the lower end thereof. The flange 53 is provided with suitable apertures for accommodating screws or bolts 54 by means of 15 which the fixture is rigidly secured to the anchor plate 43. Before securing the outlet fixture to the anchor plate, a cable 55 is threaded through the passageway 24, upwardly through the molded outlet, and 20 through the tubular portion 52 of the fixture. A sealing gasket 56 is interposed between the anchor plate 43 and the flange 53, thus precluding the possibility of any leakage of moisture from the floor surface into 25 the passageway 24. An extension pipe 58 may be threaded to the upper end of the outlet fixture and this pipe may be of any desired length depending upon the distance through which the cable must be extended.

30 As clearly shown in Figs. 7 and 8, the upper surface of the flange 53 of the outlet fixture is flush with the surface of the concrete slab 21. Thus, after the outlet fixture has been properly secured in position, the 35 floor blocks 20 previously removed for the purpose of molding the outlet may be conveniently replaced. The space immediately surrounding the outlet fixture may be filled with pitch 60 or other suitable packing 40 material.

In the event that it is desired to discontinue the use of any of the outlet fixtures, a few of the floor blocks 20 surrounding the fixture are removed whereupon the fixture 45 may readily be disassembled from its companion anchoring plate 43 by removing the screws 54. These same screws may be employed to secure a cover plate 61 to the anchor plate 43, as shown in Fig. 9. The 50 upper surface of the cover plate 61 is flush with the surface of the concrete slab 21, thus permitting the convenient replacement of the floor blocks 20.

From the foregoing it will be understood 55 that this invention enables the expeditious molding of an outlet for an unlined passageway, as distinguished from the introduction of a fitting to be connected with or threaded upon an embedded tube or duct, and that 60 the invention is particularly applicable in connection with the formation of outlets for associating outlet fixtures with a duct or passageway containing a previously installed cable.

65 Although the invention has been illus-

trated and described in connection with a particular type of floor construction, it should be understood that the invention is capable of numerous other applications within the scope of the appended claims.

70

What is claimed is:—

1. In an apparatus for molding an outlet in a building slab having a distributive passageway, a molding form designed to be inserted within the passageway and having a longitudinal groove on the underside thereof.

75

2. In an apparatus for molding an outlet in a building slab having a distributive passageway containing a previously installed cable, a metallic molding form designed to be inserted within the passageway and having a longitudinal groove on the underside thereof for enclosing a portion of the cable, and a depressed handle for facilitating the handling of the form.

80

3. In an apparatus for molding an outlet in a building slab having a distributive passageway, a collapsible molding form comprising a pair of oppositely disposed members and a central wedge-shaped member, the lower portions of said members being designed to extend into the passageway and provided with registering longitudinal grooves for enclosing a portion of a cable contained within the passageway.

85

4. A collapsible form for molding an outlet for a distributive passageway molded within a building slab, comprising a pair of oppositely disposed members and a central wedge-shaped member, said members being provided with registering longitudinal grooves for enclosing a portion of a cable contained within the passageway.

90

5. A collapsible form for molding an outlet for a distributive passageway molded within a building slab, comprising a pair of oppositely disposed hollow metallic members and a central wedge-shaped hollow metallic member having a depressed handle for facilitating the removal of the form, the lower portions of said members being designed to extend into the passageway and having registering longitudinal grooves for enclosing a portion of a cable contained within the passageway.

95

In witness whereof, I hereunto subscribe my name this 30th day of April, A. D., 1928.

WILLIAM JOHN COOK.
